UNITED STATES PATENT OFFICE.

JACOB EISELE, OF PITTSBURG, PENNSYLVANIA.

SWITCH-OPERATING MECHANISM.

SPECIFICATION forming part of Letters Patent No. 694,006, dated February 25, 1902.

Application filed April 24, 1901. Serial No. 57,219. (No model.)

To all whom it may concern:

Be it known that I, JACOB EISELE, a citizen of the United States of America, residing at Pittsburgh, in the county of Allegheny and State of Pennsylvania, have invented certain new and useful Improvements in Switch-Operating Mechanism; and I do hereby declare the following to be a full, clear, and exact description thereof, reference being had to the accompanying drawings, which form a part of this specification.

This invention relates to certain new and useful improvements in switch - operating mechanism, and has for its object to provide novel and effective means whereby the switch-tongue may be conveniently operated from the car.

The invention is particularly adapted for use in connection with street-cars; and it consists in providing a somewhat Z-shaped lever, the one arm of which is adapted to be forced downwardly into position where it may engage with the switch-tongue and thus move the latter in the desired direction. This construction, together with other details entering into my invention, will be hereinafter more specifically described and then particularly pointed out in the claim, and in describing the invention in detail reference is had to the accompanying drawings, forming a part of this specification, and wherein like numerals of reference will be employed for designating like parts throughout the different views of the drawings, in which—

Figure 1 is a side elevation of a part of a car, partly in section, showing my improved switch-operating device in position. Fig. 2 is a front elevation of the same, partly in section, showing in dotted lines the movement of the switch-operating device. Fig. 3 is a detail perspective view of the switch-operating device detached from the car.

To put my invention into practice, I suspend from the underneath face of the car-platform 1 a pair of bearings 2, in which is journaled a rod 3, having its forward end 4 bent upwardly at an incline and extended through the platform of the car, with a foot-

plate 5 on its upper end. This rod 3 at its other or rear end is bent downwardly at an incline, as at 6, and carries a shoe 7, which is flattened and pointed, as shown, and is adapted to engage the switch-tongue when the rod is actuated. A spring 8, connected to the arm 6 of the rod and to the underneath face of the car-platform, holds the arm 6 normally in the elevated position. It will be observed that the arms 4 and 6 are bent, the one upwardly at an incline and the other downwardly at an incline, but both projecting from the same side of the rod 3. When the rod is operated by pressure on the foot-plate 5, the arm 6 will be forced downwardly into engagement with the switch-tongue to force the same to the opposite position from that it is occupying, the movement of this arm 6 and also of the arm 4 being shown in dotted lines in Fig. 2. One of the devices may be attached to each end of the car, so as to throw the switch from either end of said car. If the switch-tongue is in the desired position when the car approaches, no operation of the throwing-rod is made.

Having fully described my invention, what I claim as new, and desire to secure by Letters Patent, is—

A switch-throwing device, comprising in combination with the brackets 2, secured to the under side of the platform of a car, boxings held thereto, a bar 3 journaled in said boxings, said bar being bent at right angles at two locations, forming a downwardly-disposed arm 6 with flattened pointed end, and an upwardly-inclined arm 4, the extreme upper end of arm 4 being bent at an obtuse angle thereto, and a spring fastened at one end to said arm 6, its other arm fastened to the floor of the car, as set forth.

In testimony whereof I have hereunto affixed my signature in the presence of two subscribing witnesses.

JACOB EISELE.
